UNITED STATES PATENT OFFICE.

HENRY HUMBERT, OF BROOKLYN, NEW YORK.

DESIGN FOR A BOTTLE.

SPECIFICATION forming part of Design No. 15,697, dated January 6, 1885.

Application filed November 4, 1884. Term of patent 7 years.

To all whom it may concern:

Be it known that I, HENRY HUMBERT, of Brooklyn, in the county of Kings and State of New York, have produced a new and improved 5 Design for a Bottle, of which the following is a full, clear, and exact description.

Reference is to be had to the accompanying drawings, forming part of this specification, in which the figure is a side elevation of my new-15 ly-designed bottle.

A is the main body, and B the neck of the bottle. These are slightly tapering. At its lower end the bottle has a surrounding concave, a, and rounded base c, divided from the 15 concave a by the rib d. Above the body A the bottle shows the surrounding flat bead e, divided from the body A by the concave f, and from the bead e to the neck B the bottle

shows the rounded portion g. Between this rounded portion g and the plain portion of 20 the neck B the same shows the surrounding straight portion h and bead i, divided by the surrounding concave j, so that the bottle as a whole presents a graceful and attractive appearance.

Having thus described my invention, I claim as new and desire to secure by Letters Patent—

The design for a bottle herein shown and described, the same consisting of the tapering body A, neck B, rounded base c, concave a, 30 flat bead e, concave f, rounded portion g, flat portion h, bead i, and concave j.

HENRY HUMBERT.
